(57) **CLAIM**

The ornamental design for a ski as shown and described.

DESCRIPTION

The patent or application file contains at least one drawing executed in color. Copies of this patent or patent application publication with color drawing(s) will be provided by the Office upon request and payment of the necessary fee.

FIG. 1 shows a side view of a ski.

FIG. 2 shows a top view of the ski.

FIG. 3 shows a first cross-section view of the ski shown in FIG. 2.

FIG. 4 shows a second cross-section view of the ski shown in FIG. 2.

FIG. 5 shows a bottom view of the ski of FIG. 1.

FIG. 6 shows a top view of the ski of FIG. 1.

FIG. 7 shows a rear end view of the ski of FIG. 1.

FIG. 8 shows a front end view of the ski of FIG. 1.

FIG. 9 shows a perspective top view of the ski of FIG. 1.

FIG. 10 shows a detailed perspective top view of a front end of the ski of FIG. 1;

FIG. 11 shows a second detailed perspective top view of the front tip of the ski of FIG. 1.

FIG. 12 shows a side view of the ski including boot and binding detail; and,

FIG. 13 shows a top perspective view of the ski including boot and binding detail.

The broken lines in FIG. 12 and FIG. 13 illustrate a ski boot and ski binding which form no part of the claimed design.

1 Claim, 4 Drawing Sheets
